UNITED STATES PATENT OFFICE.

OLLIE L. STUART, OF TAMPA, FLORIDA.

BAG-CLOSURE.

1,114,934.

Specification of Letters Patent. Patented Oct. 27, 1914.

Application filed October 10, 1910. Serial No. 586,376.

To all whom it may concern:

Be it known that I, OLLIE L. STUART, a citizen of the United States, residing at Tampa, in the county of Hillsborough and 5 State of Florida, have invented certain new and useful Improvements in Bag-Closures, of which the following is a specification.

This invention relates to bag closures.

The object of the invention is to provide 10 a bag of such construction that the forcing from its place of a rope, twine or the like wrapped around to gather together the mouth of the bag, by the pressure or shifting of the contents of a bag may be prevented.

A further object of the invention is to provide a bag closure of a form which shall not interfere with the filling or emptying of a bag, and which requires no special securing 20 device to effect a closure, but shall permit the use of an ordinary tie rope, twine or the like, and which shall insure a perfect and permanent closure by the use of such tie.

With these objects in view the invention 25 consists essentially of a bag of flexible material such as canvas, jute or the like, having at or adjacent to the neck thereof outside the point where the tie is to be applied, a pipe or other inclosure and a rope or similar article arranged in the inclosure in order 30 that bulk may be given to the mouth of the bag sufficient to prevent slipping over the same of a tie applied in the usual manner.

The invention consists further of a bag of 35 flexible material having secured around its neck at or near the mouth thereof, a rope or the like, in combination with a tie applied between such rope and the contents of a bag.

The invention is illustrated in the accompanying drawings in which;

Figure 1 is a perspective view of a mouth of a bag having my improved construction, the mouth being shown as separated from the body of a bag; Fig. 2 is a transverse sectional view through one side of the mouth 45 of the bag; and, Fig. 3 is a side view of a portion of a filled bag having my improved construction applied thereto, the bag being shown as secured by a tie applied between the mouth of the bag and the filled portion 50 thereof.

In this drawing 1 represents the body of a bag, the mouth whereof has applied to it

the means for preventing displacement of a tie.

In accordance with the embodiment of my invention herein shown I form a bead or protuberance 2 at a point outside of that at which a tie is ordinarily applied, and which shall be of sufficient size that when the 55 mouth of the bag is gathered together and the tie applied it will effectively prevent slipping of the tie from the bag. The bead may be formed in any suitable way. As herein shown it consists of a pipe formed by 60 folding the edge 3 of the mouth of the bag back upon the bag and by securing the same by sewing or otherwise. The edge of the mouth of the bag is preferably folded inward and then secured in place, in order 65 that its disengagement by rubbing against adjacent bags or other objects in storing shipping or handling may be prevented. Introduced into the pipe before securing the 70 edge in place is any suitable flexible body 4, 75 which will form when in place a protuberance sufficiently large to interfere with and prevent the slipping from the end of a bag of the rope or the like 5 tied around the outside of the bag between a point reached by 80 the contents thereof and the mouth, when the bag, after having been filled has its mouth end gathered closely together and has such a tie applied thereto. A conveniently applied and cheap material for forming the 85 desired enlargement around the end of the bag is a section of cotton, hemp or other rope of a length to extend entirely around the mouth of the bag. In order to prevent displacement of the rope, when employed, 90 the ends thereof may if desired be joined.

The pipe formed as herein described extends entirely around the bag, and is closed throughout thus covering the rope or other inclosed body for its entire length, leaving 95 no opening liable to be engaged by an object with which a filled and tied bag may be brought into contact.

Experience has shown in a very large majority of instances, that when a bag containing cement, flour, grain or the like and having its neck secured by the ordinary tie rope or string, is found with its mouth unsecured after handling or shipping, the knot or fastening of the tie rope remains intact, 105 showing that it has been slipped from the

bag by pressure or shifting of the contents of the bag. It is, however, desirable by reason of cheapness and ease of application to maintain the tie rope or string as a fastening.

From the foregoing description of my invention it will be obvious that when a cloth or other flexible bag having my invention applied thereto is filled with material such as cement, flour, grain or the like and has the usual rope or other similar tie applied to the neck which has been previously gathered as usual, the forcing of the tie from the neck of the bag by the pressure or movement of the contents of the bag by reason of the shifting thereof due to handling or to jarring incident to shipping, will be effectively prevented.

While I have particularly described one form in which my invention may be embodied, it will be understood that I by no means intend to limit the scope thereof to any specific construction.

Having thus described my invention, what I claim as new, and desire to secure by Letters Patent, is:—

1. A bag closure comprising a pipe extending around the neck of a bag, a separate body located in the pipe and forming a bead or protuberance, and a rope or string encircling the bag between the bead or protuberance and the body of the bag.

2. A bag closure comprising a bag having the outer edge of the mouth thereof turned inward and secured to the inner face of the bag; a rope or the like covered by such in-turned edge forming a bead, and a tie rope or string encircling the bag between the bead and the body of the bag.

In testimony whereof I affix my signature in presence of two witnesses.

OLLIE L. STUART.
